UNITED STATES PATENT OFFICE

WILLIAM C. GILMORE, OF GREENVILLE, SOUTH CAROLINA

LOOM ATTACHMENT

Application filed May 16, 1929. Serial No. 363,569.

My invention relates to attachments for looms and more particularly to a device which is primarily intended to be applied to the loom temples for the purpose of catching the loops of the filling yarn which are not woven into the selvage,—although of course the device is adapted to engage a selvage loop itself and hold the same until the weft threads forming said loop have been beaten up in the fabric by the reeds in the forward movement of the lay.

Ordinarily, in some classes of goods woven on looms, owing to the tension of the yarn, a catch cord (sometimes called a selvage cord) has to be used to hold the looped ends of the filling yarn. The shuttle laying the filling yarn first passes over the cord and in its return movement passes under the cord. It frequently occurs that the catch cord becomes broken with the result that the selvage is imperfect and the goods damaged.

Briefly stated, this invention has for its primary object to eliminate the necessity for the use of the catch cord for holding the looped ends of the filling yarn, and which is also adapted to engage a free loop of filling yarn, or a selvage loop until the same is beaten into the fabric thereby preventing the formation of "saw teeth" or filling cuts in the selvage,—the nature of the device being such that it can be readily applied to standard loom temples, and being susceptible of adjustment as the occasion may require to the end that the most efficient operation may be obtained.

A further object of the invention resides in the provision of a novel guide means for the loop-engaging element,—which guide means positively effects a stripping of the loop from the loop-engaging element when the same is retracted in the movement of the lay towards the breast beam of the loom.

A further object of the invention resides in the provision of a device of this kind adapted to be operated by the lay of the loom which incorporates novel catching means, whereby the loop-engaging element can be maintained in inoperative position.

The invention also resides in certain novel features of construction, combination and ar-

rangement of the various parts and in modes of operation,—all of which will be readily understood and appreciated by those skilled in the art, upon reference to the accompanying drawings in conjunction with the following detailed descriptive matter.

The drawings illustrate what now appears to be a preferred example of the invention. However, it is to be understood that the illustrated embodiment of the invention is susceptible to considerable change and modification within the period and scope of the subject matter claimed hereafter.

In the drawings where the same reference characters have been used to designate the same parts in all views,

Fig. 1 is a top plan view, partly broken, and illustrating the application of my invention to a loom, of which only such parts have been illustrated as are considered necessary for an understanding of the invention in hand;

Fig. 2 is a side elevational view of a loom temple to which my invention is shown applied,—there being illustrated also a portion of the lay of the loom;

Fig. 3 is a cross-sectional view thru the temple taken on the line 3—3 of Fig. 1;

Fig. 4 is a view similar to Fig. 2 but showing the loop-engaging element retracted thru the instrumentality of the lay in its forward movement;

Fig. 5 is a diagrammatic view, partly in section and illustrating the operative action of the loop-engaging element; and

Fig. 6 is a perspective view of a temple with my attachment applied thereto.

Referring specifically to the drawing, A designates the breast beam of the loom, to which are applied adjacent each end, the temple supporting brackets B each carrying a temple slide C, the forward arm C¹ of which supports the usual box D containing the rolls (not shown) having the pinpoints on their peripheries for engaging the two selvages of the cloth to hold the latter stretched against contraction. The letter E designates the fabric and H the lay of the loom,—the reeds being shown dotted. The warp threads are

designated at **F**, **F'** while the filling yarn or weft thread is designated at **G**,—the looped ends of which are indicated as **G'** in Fig. 5. These filling yarn or selvage loops **G'**, as the case may be, are formed by the shuttle (not shown) when it commences its return trip.

The function of my invention is through the element or wire 13, to engage the respective loops **G'** as they are formed, whether they be selvage loops or the loops of filling yarn not woven into the selvage, to temporarily hold the same until they are beaten into the fabric by the reeds, in the forward movement of the lay.

15 The attachment which is the subject of this invention comprises an elongated **U**-shaped plate 7 having upturned ends 7a,—said plate having a closed longitudinal slot 6 to receive the screws or bolts *a* which serve to slidably 20 mount the temple slide C upon the bracket B. Thus, it will be seen that the **U**-shaped plate or member 7 can be adjusted with or relatively of the temple slide C, as the occasion may require.

25 Of course, in practice there will be two units as shown, one associated with each temple. However, since the units are identical a description of one will suffice for both.

Extending through the upturned ends 7a 30 of the **U**-shaped plate 7 is a slide rod 8 which at its forward end is bent laterally as indicated at 8a and then extends downwardly a substantial distance as indicated at 8b to a point in substantial continuation of the path 35 of the lower beam of the lay as it approaches the temple box D. From this point the rod extends forwardly as indicated at 8c, the end being bent downwardly as indicated at 8d to serve as a bumper to intercept the lower 40 beam of the lay as it moves to beat up the cloth through the reeds which it carries.

It will be perfectly obvious that when the lay moves to the position shown in Fig. 4 from the position shown in Fig. 2 that the 45 rod 8 will be forced rearwardly.

The rearwardly extending ledge D' of the temple box D has pivoted thereon, as at 9b, one end of a plate 9 having opening from its opposite end a longitudinal slot 9a which is 50 adapted to receive the vertical portion 8b of the rod 8. The plate 9 functions somewhat after the fashion of an auxiliary guide but its primary function is to serve as a latch for locking the rod 8, through the rod portion 8b, in a rearward position,—there being provided a lateral notch 9c opening from the slot 9a as clearly indicated in Figure 6. Notch 9c is manually engaged with rod portion 8b.

55 Adjustably carried by the rod 8 between the ends 7a of plate 7 is a collar 10,—there being provided a set screw 10a for clamping the collar to the rod at a predetermined point so that the tension of the spring 11, which is 60 disposed between the collar and the rear-

most upturned end 7a of plate 7, may be regulated.

To the rear end of the rod 8 is secured the block 12,—the same being adjustable and adapted to be held at a predetermined point on the rod 8 by means of a set screw 12a. The selvage or filler yarn-loop-engaging wire 13 is brazed or otherwise secured to the block 12 as shown and extends through a flexible guide sleeve 14 which is preferably formed of coiled wire. The sleeve 14 extends through aligned holes in the upturned plate ends 7a and projects forwardly through the hole 15a in the stud 15 which is threaded through the bracket 16. This bracket plate 16 secured against the outer end of the temple box D by means of the machine screws 16a which form a part of the pin-roll journalling means. It is therefore manifest that no extra elements are necessary to mount plate 16. A nut 17 on the end of the stud 15 serves to lock the stud 15 in a predetermined set position for directing the projecting end of the guide sleeve 14 downwardly at the proper inclination so that the end of the wire 13 will properly engage the loop of filling yarn (or selvage loop for that matter) as the same is formed by the shuttle.

Of course the engagement of the wire or needle 13 with the filling yarn or selvage loop **G'** is momentary,—it being obvious that when the lay moves forward on its beating stroke, the wire 13 will be retracted into its guide sleeve 14 through the rearward movement of rod 8 which is produced by the engagement of the lower beam of the lay with the trip end 8d of the rod.

Various adjustments of the stroke of the wire 13 can be had by the manipulation or adjustment of the block 12 on the rod 8, or by adjustment of the collar 10.

The flexible guide sleeve 14 is of the utmost importance since the projecting outer end thereof serves to positively strip the loop **G'** from the wire 13 when the same is retracted into said guide sleeve.

Having described my invention, what I claim as new and desire to secure by Letters Patent of the United States is:

1. A filler thread or selvage loop retainer 115 attachment for loom temples comprising a **U**-shaped carrier plate having a closed longitudinal slot adapted to receive the attaching screws which mount the temple slide upon its support whereby said **U** shaped plate can 120 be adjusted with the temple or relatively thereof, a flexible guide sleeve extending through the lateral ends of said attaching plate, a longitudinally and rotatably adjustable stud having a transverse hole through 125 which said guide sleeve is adapted to extend, carrying means for said stud supportable by the outer end of the temple box, a loop-engaging wire extending through said guide and projecting from both ends thereof, an 130

- actuator rod for said loop-engaging wire and slidably carried by the lateral ends of said carrier plate, an adjustable block mounted on the rear end of said actuator rod and to which the corresponding end of said wire is attached, an adjustable collar carried by the actuator rod between said lateral ends of the U-shaped carrier plate, a coil spring on said actuator rod and confined between said 10 collar and the laterally turned rear end of said carrier plate for normally tending to actuate said rod in a forward direction to project the forward end of the loop-engaging wire beyond the stud-carried end of said 15 guide sleeve, the forward end of said actuator rod having a downwardly extending vertical portion and terminating in a forwardly extending lay-intercepting bumper, and a latch member carried by the temple and adapted 20 to engage the downwardly extending portion of the actuator rod for holding it in retracted position against the action of said spring whereby to maintain the free end of the loop-engaging wire retracted into the stud-carried 25 end of its guide sleeve.
2. In a selvage or filler-yarn-loop retainer for looms, a support, a loop-engaging element carried by said support, and adjustable guide means for the loop-engaging end of the aforesaid element, said guide means comprising a bolt threaded in a mount.
3. In a selvage or filler-yarn-loop retainer for looms, a support, a loop-engaging element slidably carried by said support, and adjustable guide means for the loop-engaging end of the aforesaid element, said guide means comprising a bolt threaded in a mount.
4. In a selvage or filler-yarn-loop retainer for looms, a support, a loop-engaging element 40 slidably carried by said support, adjustable guide means for the loop engaging end of the aforesaid element, and a slideable lay-operated actuator rod for said loop-engaging element.
5. In a selvage or filler-yarn-loop retainer for looms, a support, a loop-engaging element 45 slidably carried by said support, adjustable guide means for the loop-engaging end of the aforesaid element, a slideable lay-operated actuator rod for said loop-engaging element, and an adjustable connection between said 50 element and rod whereby the effective movement of the element may be varied.
6. In a selvage or filler yarn loop retainer for looms, a support, a loop-engaging wire 55 slidably carried by said support and projectable beyond the same to engage a loop, and a pivotally supported guide through which the outer end of said wire extends, adjusting means for said guide for directing the wire to properly engage a loop, and actuating means for said wire.
7. The combination set forth in claim 6, and an adjustable connection between said 60 wire and its actuating means whereby to limit the extent of projection of the wire beyond said guide in the loop-engaging position.
8. The combination set forth in claim 6, and said support being adjustably mounted for movement toward and from the lay of the 70 loom.
9. A loop-engaging loom attachment of the class described comprising a support, a loop-engaging wire slidably carried by said support, adjustable means for securing the 75 support to the loom whereby the support can be adjusted toward and from the lay, a pivoted guide member receiving the loop-engaging end of the wire, means for adjusting said member to a position to assure the engagement of the wire in the loop when the wire is projected toward the same, yieldable means normally tending to project the wire to loop-engaging position, an actuating member for said wire and positioned to intercept 80 a portion of the lay in its movement to beat the cloth, and latch means manually operable to retain the wire retracted out of loop-engaging position.
10. In a selvage or filler yarn loop retainer 85 for looms, a loop-engaging element movably mounted for actuation to and from loop-engaging position, actuating means for said loop-engaging element, and manually operable latch means acting through said actuating means for retaining the loop-engaging element out of loop-engaging position.
11. In a selvage or filler yarn loop retainer 90 for looms, a support adapted to be mounted for adjustment with or relatively of the loom temple toward and from the lay, a loop-engaging wire slidably carried by said support, an actuating rod also slidably carried by said support, an adjustable connection between said actuating rod and said loop-engaging wire, yielding means acting through said actuating rod for normally tending to maintain the actuating wire in loop-engaging 95 position, a flexible guide sleeve carried by said support and through which said loop-engaging wire extends, an adjustable member through which one end of said sleeve projects in the direction of the lay, means for adjusting said last-mentioned member to direct said sleeve so as to effect the engagement of said wire with a loop when the wire is projected from the end of the sleeve, said actuating rod having a vertical portion disposed beyond one end of said support and terminating in a forwardly extending lay 100 intercepting bumper portion whereby the rod will be forced rearwardly by the lay as the latter moves to cloth beating position, and a latch member adapted to engage the vertical portion of said rod to hold the same retracted 105 whereby to maintain the wire out of loop-engaging position.
